(57) **CLAIM**

The ornamental design for a nine shelf compact disc rack, as shown and described.

DESCRIPTION

The claimed compact disk rack has nine shelves each consisting of three compartments which can be used to store compacts disks in a spine out or face out manner.

FIG. 1 is a front elevational view of a nine shelf compact disc rack showing my new design;

FIG. 2 is a right side elevational view thereof, the left side being a mirror image;

FIG. 3 is a front perspective view thereof; and,

FIG. 4 is a back perspective view thereof.
